UNITED STATES PATENT OFFICE.

AXEL NELSON, OF PAXTON, ILLINOIS.

GATE.

1,357,108.

Specification of Letters Patent. Patented Oct. 26, 1920.

Application filed April 20, 1918. Serial No. 229,812.

To all whom it may concern:

Be it known that I, AXEL NELSON, a citizen of the United States, residing at Paxton, in the county of Ford and State of Illinois, have invented a new and useful Gate, of which the following is a specification.

This invention relates to farm gates one of its objects being to provide a strong gate which is simple in construction and which can be operated like an ordinary gate to allow vehicles and the like to pass through the gate opening, and which can also be opened in sections so as to allow small stock only to pass from the inclosure or to allow large stock only to pass.

With the foregoing and other objects in view which will appear as the description proceeds, the invention consists of certain novel details of construction and combinations of parts which will be hereinafter more fully described and pointed out in the claim, it being understood that various changes may be made in the construction and arrangement of the parts without departing from the spirit or sacrificing any of the advantages of the invention as set forth in the appended claim.

In the accompanying drawings the preferred form of the invention has been shown.

In said drawings—

Figure 1 is an elevation of the gate, certain parts being shown in section.

Fig. 2 is a section on line 2—2 Fig. 1.

Fig. 3 is a section on line 3—3, Fig. 1.

Referring to the figures by characters of reference, 1 and 2 designate the gate posts, the post 2 having bolts 3 extended therethrough provided with eyes 4. Mounted for rotation in these eyes is a pipe, rod or the like, 5, the upper end of which is screwed into a T-fitting 6 to which is connected the top rail of the upper gate section, said rail being shown at 7. The other end 45 of the rail 7 is connected to a fitting 8 secured to the upper end of a tubular gate-member 9. The lower end of the member 9 is secured within a T-fitting 10 which, in turn, is connected by a rail 11, to a T-fitting 12 mounted loosely on the member 5. A T-fitting 13 is mounted loosely on the member 5 and rests on the lower eye 4, at the same time supporting the fitting 12. The

top rail 14 of the lower section of the gate extends from the fitting 13 and is connected to a T-fitting 15 adapted to move to position beneath and close to the fitting 10. A short pipe 16 or the like is extended downwardly from the fitting 15 and is connected by an elbow 17 to the bottom rail of the lower gate section and which rail has been shown at 18. This rail, in turn, is connected to a T-fitting 19 mounted for rotation on the member 5 and supported thereon by a collar 20 or the like screwed or otherwise secured to said member. A wire fabric 21 can be secured to the parts of the lower section of the gate, thus to prevent small animals from passing through the gate opening when the gate is closed. Wires 22 can be secured to the members of the upper section of the gate, as shown. The upper ends of the fittings 6 and 8 can be closed by plugs 23 to which a wire 22 can be attached, as shown.

A bolt 24 may be slidably mounted in the member 9 of the upper section of the gate, said member being slotted to receive a knob 25 or the like. When both sections of the gate are closed, the bolt can be lowered into the fitting 15, thus to secure the two gate sections together so that they will swing together like an ordinary gate.

It will be obvious that by lifting the bolt the upper gate section can be opened independently of the lower section, thus allowing large stock to step over the lower section and leave the inclosure. By leaving the upper section closed, and opening the lower section, small stock can pass out under the upper section. The particular manner of assembling the two sections at the hinge end of the gate is simple and efficient and deemed of importance. It is to be understood, of course, that suitable latches can be provided for the respective sections of the gate.

What is claimed is:—

The combination with a post having vertically spaced bearing members, of an upper gate having an end member extending downwardly therefrom and mounted for rotation in the vertically spaced bearing members, a lower gate mounted to swing upon said end member, the two gates being of the same length and adapted to swing

relative to each other about the same axis, means slidably connected to one end of one of the gates for detachably engaging the corresponding end of the other gate to hold the gates together and prevent independent swinging thereof.

In testimony that I claim the foregoing

as my own, I have hereto affixed my signature in the presence of two witnesses.

AXEL NELSON.
